(57) **CLAIM**

The ornamental design for a controller for tattooing apparatus, as shown and described.

DESCRIPTION

FIG. 1 is a front top left perspective view of the controller for tattooing apparatus;

FIG. 2 is a front bottom left perspective view of the controller for tattooing apparatus of FIG. 1;

FIG. 3 is a rear bottom right perspective view of the controller for tattooing apparatus of FIG. 1;

FIG. 4 is a front elevational view of the controller for tattooing apparatus of FIG. 1;

FIG. 5 is a rear elevational view of the controller for tattooing apparatus of FIG. 1;

FIG. 6 is a right side elevational view of the controller for tattooing apparatus of FIG. 1;

FIG. 7 is a left side elevational view of the controller for tattooing apparatus of FIG. 1;

FIG. 8 is a top plan view of the controller for tattooing apparatus of FIG. 1, wherein portions A and B are encircled and indicated;

FIG. 9 is a bottom plan view of the controller for tattooing apparatus of FIG. 1, wherein portions C, D and E are encircled and indicated;

FIG. 10 is an enlargement of the portion A illustrated in FIG. 8;

FIG. 11 is an enlargement of the portion B illustrated in FIG. 8;

FIG. 12 is an enlargement of the portion C illustrated in FIG. 9;

FIG. 13 is an enlargement of the portion D illustrated in FIG. 9; and,

FIG. 14 is an enlargement of the portion E illustrated in FIG. 9.
